MIXING MACHINE

Application filed May 23, 1930. Serial No. 454,857.

This invention is particularly directed to mixing machines of the Banbury type which are largely used in the compounding and mixing of rubber materials, although their field of usefulness extends beyond this particular purpose.

Machines of this type comprise essentially a cylindrical trough with a rotor working in the trough, and in the practical embodiments of the machine two rotors are used which operate in troughs lying side by side. The feed for the machine comprises a passage-way leading to a hopper arranged above the troughs, and in practical operation a weight 10 is used for pressing the material down into the troughs within the sphere of operation of the rotors. Some means are usually employed for mechanically raising the weight and guiding it in its downward movement 15 so as to permit access of fresh batches of compound.

The present invention has for one of its objects a novel construction of weight which affords several practical advantages in the 20 operation of the machine. The invention also includes other features of improvement, which will be hereinafter more fully pointed out.

Referring to the drawings which illustrate one form of the invention—

Figure 1 is a vertical section of a conventional type of Banbury mixer, the section being taken transversely of the machine;

Fig. 2 is a vertical transverse section of the preferred form of weight provided by the invention;

Fig. 3 is a perspective view of the weight on a smaller scale.

Figs. 4 and 5 are respectively a front and top view of the weight.

Referring to the drawings, let A indicate the mixer as a whole, comprising semi-cylindrical troughs B and C, in which are mounted to rotate, rotors D and E. The latter are 45 of such a shape as to knead or smear the materials against the cylindrical walls of the troughs. Midway between the troughs is located the feed passage F leading to a hopper device G. A weight H is provided, which is 50 designed to rest upon such material as may

be in the neck or immediately above it and place a pressure on the material so that it is forced down into the troughs between the rotors. Usually the weight is mounted upon a rod I, which carries a piston J above it by 55 means of which it may be raised by fluid pressure beneath the piston from the point shown in dotted lines in Fig. 1 to a point slightly beyond the full line position in this figure. Fluid pressure may also be exerted 60 on the upper side of the piston to increase the downward pressure upon the weight. The connections for these purposes, being no part of the present invention, are not shown.

It will be understood that in the use of 65 machines of this type many different compounds are mixed, the compounds usually being some form of a rubber mix. These customarily involve the use of dry powders of various types and kinds, some of which 70 will feed rapidly and others slowly, and it is also to be noted that the character of the mix may require either the slow feeding or rapid feeding.

Very frequently the hopper G will be 75 wholly or partly filled with the mix, and under many circumstances the powders used are dumped into the hopper above the weight and the latter is utilized to more or less control the distribution of the weight throughout the mix by the character of its feed. It will also be understood that during the operation of the machine, while the mix is in progress, the action of the rotors produces an oscillating upward and downward movement of that portion of the material immediately above them, there being, of course, a tendency of the material to escape upward through the neck in certain angular positions of the rotor. This oscillating up and down 80 movement is utilized in the operation of the machine to feed the powders especially past the weight.

In the utilization of various types of 85 weight, we have found in practice that if the weight be constructed with an inclined inner face extending entirely in one direction from back to front, a better performance of the feeding mechanism is secured.

Figs. 2 and 3 illustrate the best proportions 90

of the weight, as we have found in practice. In these figures the inclined surface K extends from the top of the weight L to a point M near the bottom of the weight. Preferably, the inclined surface is clear and unbroken except for the boss N to which the lower end of the rod I is secured, this boss dividing the weight into two inclined compartments O and P. Preferably, the boss is rounded or inclined so as to spill the powders into either compartment. The weight is best provided with sides Q and R, which may have lips S and T along their upper and lower edges for nicely fitting the end walls 15 of the neck and hopper, thereby preventing clogging of the powder in between the end walls.

When the weight is in the position shown in Fig. 1, the feed of powder will progress 20 over the forward edge U, even though the dimensions of the weight from front to rear accord with the dimensions of the walls of the feeding neck or passage F. But when the weight has arrived at the point in its 25 downward movement where its lower edge lies within the walls of the passageway, a close fit would retard the passage of the powder. Hence, the front walls U are preferably cut back beyond the plane of the front edges of the side walls Q and R so as to produce a feeding slot when the weight is 30 within the neck. This slot may, of course, be omitted.

If it is desired to reduce or avoid the feeding slot a filling piece or pieces such as V (Fig. 2) may be bolted or otherwise fixed 35 within the slot. Conveniently, the feeding slot may be divided into parts by a projection W extending from the boss N so that the weight will be better guided while in the neck F.

We have found that the weight as thus 40 provided is more effective than previously known forms. It prevents, to a large extent, clogging of the space between the weight and the inner side of the hopper or neck with powder, as frequently occurs with prior forms. It also produces a discharge 45 facing the front or hopper side of the machine where the action of the feed can be better inspected. Further, it provides means by which any powder which lodges upon the weight can be easily dislodged from the front 50 of the machine either by the hand of the workman or by the use of a brush or other implement. This avoids an undesirable feature in prior forms, where it has been difficult to dislodge any accreted powder or other 55 material which may form on the faces of the weight.

In the type of mixer shown there is provided a lower gate or door X which is adapted 60 to slide on guideways Y, the sliding motion being lengthwise of the troughs B and C. The opening of the gate provides a lon-

gitudinal slot through which discharge of the materials is made after the compounding is completed. The upper part Z of the gate is preferably of a contour where it forms a continuation of the circular walls of both of 70 the troughs B and C. These features are well known in the art.

According to the present invention, we 75 form the upper part Z as a removable section, preferably connected at about the lower part by a tongue or groove or other suitable connection, and keying it in place by a key such as Z'. By this means the upper part, which is subjected to considerable wear due to the fact that it forms a part of the working surface of the machine, may be replaced without renewal of the lower part of the gate, which has a long life. So, also, the upper part may be made of more expensive and more durable material than the lower part without any 80 excessive increase in cost.

If it is desired to water-cool the weight, the latter may be formed with cores A', B', and ingress and egress pipes C', D' may be connected with the cores as shown in detail in 85 Fig. 2.

The term weight is used in a generic sense 90 and is meant to cover the pressure feeding device irrespective of whether it operates mainly by gravity or otherwise.

While we have shown and described one 95 form of the invention, it will be understood that we do not wish to be limited thereto, since various changes may be made therein without departing from the spirit of the 100 invention.

What is claimed is:

1. In a mixing machine, the combination 105 of mixing mechanism and a weight designed to press the material toward said mixing mechanism, said weight having an incline O, P extending from rear to front, with the upper part of the incline at the rear of the weight, and having side walls Q, R defining the ends of the incline, said side walls having 110 projecting flanges S, T, and the weight further having a feed slot U lying to the rear of the front portions of the side walls.

2. In a mixing machine, the combination 115 of mixing mechanism, a feed opening, and a weight adapted to press upon the material which is being fed, said weight having on one side an inclined surface running substantially from top to bottom of the weight, the upper part of the incline being at the rear, 120 and the lower part of the incline being nearest the feed opening, and the weight having at its lower front edge nearest the feed opening a feeding slot with parts of the weight projecting in front of such slot.

3. In a mixing machine, the combination 125 of mixing mechanism, a feed opening, and a weight adapted to press upon the material which is being fed, said weight having on one side an inclined surface running sub-

stantially from top to bottom of the weight, the upper part of the incline being at the rear, and the lower part of the incline being nearest the feed opening, and said weight 5 having side walls defining the ends of the incline.

4. In a mixing machine, the combination of mixing mechanism, a feed opening, and a weight adapted to press upon the material 10 which is being fed, said weight having on one side an inclined surface running substantially from top to bottom of the weight, the upper part of the incline being at the rear, and the lower part of the incline being near- 15 est the feed opening, and said weight having side walls defining the ends of the incline, and said side walls having lips or flanges extending laterally beyond the sides of the weight and designed to contact with 20 the side walls of the feed passages.

In witness whereof, we have hereunto signed our names.

CARL F. SCHNUCK.
FERNLEY H. BANBURY.
